HAROLD V. ALLEN

INVENTOR

BY *Victor J. Evans*

ATTORNEY

WITNESS:

Lee Brink

UNITED STATES PATENT OFFICE

HAROLD V. ALLEN, OF EAST BETHEL, VERMONT

PROTECTIVE DEVICE

Application filed March 21, 1930. Serial No. 437,845.

This invention relates to a protective device designed primarily for use by boot blacks and the invention has for its primary object to provide a shield which may be readily inserted between the sock or stocking and the upper portion of the upper of a shoe by the boot black using the device, so as to prevent any of the shoe polish reaching and soiling the sock or stocking.

10 Another object of the invention is to provide a protective device of this class which may be in the nature of a blank of paper or other inexpensive sheet material and therefore may be discarded after use, if it in any 15 manner becomes soiled.

Another object of the invention is to provide a device of this class of a blank form and in which the blank will be of such contour as to most effectually cover all portions 20 of the sock or stocking above the upper edge of the upper of the shoe or slipper which might possibly be soiled by the polish employed.

Another object of the invention is to provide 25 a protective blank for the purpose stated in which certain portions of the blank may be readily separated from the remaining portion of the blank along a line of perforations, whereby the single blank may be employed for exceptionally low shoes or for 30 higher shoes by leaving the said portions intact, or, on the other hand, separating the same from the intermediate portion of the blank.

35 This invention also consists in certain other features of construction, and in the combination and arrangement of the several parts, to be hereinafter fully described, illustrated in the accompanying drawing, and specifically 40 pointed out in the appended claims.

In describing my invention in detail, reference will be had to the accompanying drawing, wherein like characters denote like or corresponding parts throughout the several 45 views, and in which:—

Figure 1 is a plan view of the protective blank embodying the invention.

Figure 2 is a perspective view illustrating one of the blanks applied about the foot and ankle of the wearer of the shoe to be

polished, and the shoe being of the low type worn by ladies.

Figure 3 is a similar view illustrating the manner in which the blank is employed in connection with a higher shoe such as worn by men.

As before stated, the blank is preferably formed from paper. The blank embodying the invention is indicated in general by the numeral 1 and comprises an intermediate portion 2 which is of a length to fit about the ankle and instep of an ordinary foot, it being understood that if desired the blanks may be made in a few different sizes and that a blank of one size will be found to be applicable to the wearers of shoes of several different sizes. The upper margin of the body or intermediate portion 2 is of arcuate form, as indicated by the numeral 3 and the end margins are extended along a substantially straight line from the ends of the upper margins 3 as indicated by the numeral 4. The lower margin of the intermediate or body portion 2 of the blank is of convex arcuate form as indicated by the numeral 5, and the portions of the blank which are removable or separable, as before stated, are indicated by the numeral 6 and it will be observed by reference to Figure 1 that these portions have an approximately semi-circular marginal contour as indicated by the numeral 7, the upper edge portion 8 of each of the portions 7 merging with the corresponding straight upper end edge 4 of the intermediate or body portion 2, and the relatively adjacent sides of the two members 6 having their margins 9 merging on an approximately ogee curve 10 with the end portions of the edge 5 of the said body or intermediate portion 2.

An arcuate line of perforations is indicated by the numeral 11 and is curved on a smaller arc than the edge portions 7, 8 and 9 of the respective separable side members 6, and the lower parts of the side portions 6 extend somewhat below the lower margin 5 of the body or intermediate portion of the blank.

By reference to Figures 2 and 3 of the drawing, it will be observed that the intermediate portion 2 of the blank is to be ap-

plied about the rear side of the ankle and heel of the wearer of the shoe to be polished, and the lower margins of this portion are to be fitted between the sock or stocking and the upper edge of the heel portion of the shoe upper. The portions 6, if they are left remaining, at the time of application of the device to a low shoe as in Figure 2, are brought into mutually overlapping position from the instep of the foot and are inserted at their marginal portions between the sock or stocking and the shoe upper at the opposite sides of the instep and in rear of the toe of the shoe. Where the device is to be employed in connection with higher shoes, as in Figure 3 of the drawing, the portions 6 will be torn from the intermediate or body portion 2 along the lines of perforations 11, and the end portions of the body or intermediate portion 2, between the marginal portions 4 and the line of severance 11, will be brought into overlapping relation above the instep and with the portion 2 fitting about the ankle and heel of the wearer's foot.

Due to the concave formation of the upper margin 3 of the body portion 2 and the convex curvature of the lower margin 5 of said portion, it will be evident that the said portion 2 will, between its ends, snugly conform to the shape of the ankle and heel of the foot to which the device is applied at the rear thereof.

What I claim is:—

1. A protective device for use in protecting socks and stockings while polishing shoes, which device comprises a blank of flexible sheet material having side portions to be fitted over the sides and top of the instep of the foot, and a connecting intermediate portion to extend around the ankle and heel, the said blank being provided with end portions extending from the ends, and under sides of the intermediate portion, and connected therewith along a weakened line.

2. A protective device for use in protecting socks and stockings while polishing shoes, which device comprises a blank of flexible sheet material having side portions to be fitted over the sides and top of the instep of the foot, and a connecting intermediate portion to extend around the ankle and heel, the said blank being provided with end portions extending from the ends, and under sides of the intermediate portion, and connected therewith along a weakened line, the margins of said end portions being of approximately semi-elliptical contour.

In testimony whereof I affix my signature.

HAROLD V. ALLEN.
